HOIST

Frank P. Lawler, Chicago, Ill., assignor of one-third to Charles H. Grant, San Francisco, Calif., one-third to Frank P. Lawler, Chicago, Ill., and one-third to Paul J. Tyler, Oroville, Calif.

Application June 5, 1942, Serial No. 445,863

2 Claims. (Cl. 254—186)

This invention relates to a hoist and especially to a modification or improvement on the structure disclosed in my copending application entitled Hoist, Serial No. 444,653 filed May 27, 1942.

The object of the present invention is generally to improve and simplify the construction and operation of hoists; to provide a hoist which is adapted to be directly driven by a high speed prime mover such as an electric motor; to provide a motor driven hoist which is substantial in construction and which will require a minimum of space; to provide a hoist structure in which the driving motor is adapted to be mounted within the hoist drum and frame supporting the drum; to provide means for anchoring the motor housing against rotation within the hoist drum; to provide a frame which forms a mounting and support not only for the hoist drum and the motor within the same, but also for a reduction gear drive interposed between the motor shaft and the hoist drum, and further, to provide a motor mounting and coupling which permits ready insertion or removal of the motor for inspection and repairs.

This invention is shown by way of illustration in the accompanying drawings, in which:

Fig. 1 is a central vertical longitudinal section of the hoist; and

Fig. 2 is a cross-section taken in line II—II of Fig. 1.

Referring to the drawings in detail and particularly Fig. 1, A indicates in general an elongated frame consisting of a pair of ring shaped end flanges 2 and 3 which are connected by a longitudinally extending base section 4 (see Fig. 2) and a plurality of barrel-type arms 5, the base section being in turn provided with foot lugs 6 whereby the frame as a whole may be secured to any suitable support. Extending radially from the base section 4 and the arms 5 is a disc or spider arms 7, and supported thereby is a bearing 8. This bearing is disposed adjacent one end of the frame, and a second bearing 9 is disposed at the opposite end, this latter bearing being formed integral with or secured to a head member 10 which is secured by bolts or the like to the end flange 3. Mounted within the frame and journaled on the bearings 8 and 9 is a cable drum 11 at one end of which is formed a brake drum 12. Journaled within the bearing 8 is a sleeve 14 and secured to one end thereof is a brake drum 15. Formed on the opposite end of the sleeve is an annular flange 16, and carried thereby is an internal ring gear 17. A similar

ring gear 18 is secured to the cable drum and both ring gears are in constant mesh with a pair of connected spur gears 17c and 18c, said spur gears being journaled on an eccentric 19 which is keyed or otherwise secured on a drive shaft B journaled at one end in sleeve 14 and at the opposite end in a bearing indicated at 26.

Each of the brake drums is provided with a brake band 21, and each band has one end anchored to the frame arm 5a, as shown in Fig. 2. Levers 22 and 23 are pivotally supported on the same frame arm and are connected to the free ends of the respective brake bands.

The internal ring gears 17 and 18, together with the eccentric 19, and the connected spur gears 17c and 18c journaled on the eccentric form a reduction gear drive whereby power is transmitted from the drive shaft B to drive the cable drum. By this gear arrangement a high ratio of reduction is made possible, and a reduction of thirty to one or more is readily obtainable. Thus, it becomes possible to connect the drive shaft B directly to a high speed prime mover such as an electric motor or the like. In the present instance an electric motor is employed and the motor is mounted directly within the drum barrel and the frame A supporting the same. The housing C of the motor is supported at its outer end in bearing 9, and is keyed as indicated at 25 to said bearing to anchor the housing against rotation. The opposite or inner end of the motor housing is supported on the bearing 26 formed on the end wall 27 of the hoist drum, and the shaft D of the motor is coupled to the drive shaft B by coupling 28.

In actual operation with power transmitted from the motor to the shaft B, if it is desired to haul in on the cable indicated at 29, it is only necessary for the operator to apply the brake band 21 on the drum 15 by means of a lever 22, and simultaneously release the brake band on the drum 12 by means of lever 23. By so doing, brake drum 15, sleeve 14 and ring gear 17 become stationary, and gear 17c will, accordingly, roll within the gear 18 in a direction reverse to the rotation of the eccentric and the drive shaft B upon which it is secured, and as gear 18c is connected or formed integral with the gear 17c, it will rotate in unison therewith, and as such will drive the ring gear 18 and the cable drum to which it is secured. The reduction speed between the drive shaft B and the ring gear 18 will, of course, depend on the ratio between the gears 17, 17c and 18 and 18c. This reduction may

readily be thirty to one, or greater, and any drum or cable speed may thus be obtained.

The hoist here shown is constructed and designed to permit two or more hoist units to be connected end to end in a minimum of space and to permit the drive shafts of two adjacent units to be coupled together as indicated at 30 in Fig. 1, or to permit the drive shaft of one unit to be coupled to the motor shaft D, as indicated at 31. With this purpose in mind it will be noted that the frame A is so constructed that the head member 10 may be secured to either or both ends thereof, as shown in Fig. 1, thus making it possible to connect the hoist units to the right or left of any one unit so that the cable drums may be rotated in the same or in opposite directions, using a single motor to power all the hoist units so connected.

It will be apparent from the construction shown that when two or more hoist units are coupled end to end, that by changing the gear ratios, that is, the ratio of the gears 17, 17c and 18, 18c, that the drum speeds of the various coupled hoist units can be varied over a wide range, thus permitting adjacent hoists to deliver varying drum or cable speeds to suit different service requirements. It should furthermore be noted that all of this can be accomplished with a single prime mover driven at a constant speed.

The end to end coupling of adjacent units, as described, reduces space requirements, but a still further space reduction is accomplished by placing the prime mover or motor within the hoist drum, as shown in Fig. 1. The reduction gear drive is similarly placed within the drum and it is thus obvious that the frame A forms a support not only for the hoist drum and the motor driving it, but also for the reduction gear drive interposed between the drum and the drive shaft. The rotor of the motor may be constructed with fan blades, such as indicated at 32 and 33, and a constant circulation of the air may thus be maintained through the brake drums, the cable drum and the motor housing to prevent heating of the motor, as indicated by the air circulation arrows on Fig. 1.

For the purpose of simplicity independent lever controls are shown to actuate the brake bands but a single lever control, such as shown in my former Patent No. 2,242,193, may be employed to operate the two brake bands of each hoist unit. Also a single lever control for two adjacent hoist units may be used as shown in my Patent No. 2,199,668.

In order to make the motor readily movable for inspection, repairs, etc., it will be noted that the cable drum 11 is provided with a removable drum head 10a. With this structure, removal of the

motor is accomplished as follows: First remove the head member 10 together with key 25, then the drum head 10a, after which the motor may be freely removed by pulling it outwardly away from the coupling 28, installation being accomplished by reversing the operation.

The reduction gear drive is, as will be noted, enclosed at one side by the drum end 27 and on the opposite side by a removable cover 27a, and as such may be packed with grease and will exclude all foreign matter.

While this and other features of my invention have been more or less specifically described and illustrated, I nevertheless wish it understood that changes may be resorted to within the scope of the appended claims, and that the materials and finish of the various parts employed may be such as the experience of the manufacturer or varying conditions of use may demand.

Having thus described my invention, what I claim and desire to secure by Letters Patent is:

1. In a hoist of the character described, a frame, a bearing in the frame adjacent one end thereof, a head member secured to the opposite end of the frame, a bearing on said head, a cable drum journalled on both bearings, a motor mounted within the drum, said motor having a housing and a rotor, an extension on one end of the motor housing extending into the bearing on

30 the head member, means for securing the motor housing and extension against rotation, an extension on the opposite end of the motor housing, a bearing on the cable drum to receive and support said last named extension, and means 35 for transmitting power from the rotor of the motor to drive the cable drum.

2. In a hoist of the character described, a frame, a bearing in the frame adjacent one end thereof, a detachable head member secured to the opposite end of the frame, a bearing on said head, a cable drum having a drum head at each end and journalled on said bearings, the drum head adjacent the head member being detachable, a motor within the drum, said motor having a housing and a rotor and shaft journalled

45 therein, a sleeve-like extension on one end of the motor housing and extending into the bearing on the head member, a key in said bearing anchoring the sleeve and motor housing against rotation, a sleeve-like extension on the opposite

50 end of the motor housing, a bearing on the cable drum to receive and support said last named extension, a drive shaft, a coupling between the rotor shaft of the motor and the drive shaft, and 55 a reduction gear drive interposed between the drive shaft and the cable drum to drive the same.

FRANK P. LAWLER.
